ROTARY SLIDING VANE PUMP

Edward A. Dawson, Greenwich, Conn.

Application October 19, 1948, Serial No. 55,377

6 Claims. (Cl. 103—137)

1

This invention relates to rotary pumps of the type having a rotor eccentrically positioned in a pump chamber in a housing with a single blade sliding through the rotor, and in particular the invention relates to a rotary pump in which the inner peripheral surface of the pump chamber is designed so that the distance between the contacting surfaces at the ends of the blade remain constant and also in which cushioning means is provided in a cavity in the rotor to restrain outward travel of the blade by centrifugal motion so that wear caused by the wiping contact of the ends of the blade with the housing is reduced to a minimum.

The purpose of this invention is to provide an improved rotary pump having high efficiency with increased suction, and which will handle large volumes at all elevations.

Various types of rotary pumps have been provided and different methods have been used for reducing the wear at the ends of the blades, but the friction caused by the wiping contact at the ends of the blades causes wear on the blades and also on the peripheral surface of the housing. With this thought in mind, this invention contemplates a rotary pump having a rotor with a continuous blade sliding back and forth therethrough and with cushioning means in the rotor to reduce the friction between the ends of the blades and inner peripheral surface of the housing.

The object of this invention is, therefore, to provide means for mounting a blade in a rotor of a rotary pump so that wear caused by the wiping contact of the ends of the blade with the housing is reduced to a minimum and so that a point of contact between the rotor and the housing is formed, with a rolling action.

Another object of the invention is to provide means for permitting the escape of foreign matter between the rotor of a rotary pump and a housing.

Another object of the invention is to provide means for shaping the inner peripheral surface of the pump chamber of a rotary pump so that the contacting length of a blade in the rotor remains constant.

A further object of the invention is to provide an improved rotary pump which is of a simple and economical construction.

With these and other objects in view, the invention consists of the new and useful combination, construction, and arrangement of parts as hereinafter more fully described, set forth in the claims appended hereto, and disclosed in the ac-

2

companying drawing forming part hereof, wherein:

Figure 1 is a view showing a side elevation of the pump;

5 Figure 2 is a longitudinal section through the pump illustrating the construction thereof and taken on line 2—2 of Figure 1;

Figure 3 is a view similar to that shown in Figure 1 with the cover plate removed;

10 Figure 4 is a cross section through the pump taken on line 4—4 of Figure 2;

Figure 5 is a view similar to that shown in Figure 4 looking in the opposite direction and with the rotor and other moving parts removed;

15 Figure 6 is a detail showing an end elevation of the rotor;

Figure 7 is a detail showing a side elevation of the rotor with parts broken away and parts shown in section;

20 Figure 8 is a view showing the blade;

Figure 9 is a detail showing a removable flange forming one end of the rotor; and

25 Figure 10 is a sectional view showing the bearing mounting of the roller which provides rolling contact between the rotor and housing.

Referring now to the drawings wherein like reference characters denote corresponding parts, the improved rotary pump of this invention includes a rotor 10 having a removable head 11, a blade 12 and a housing 13 having a cover plate 14.

30 The rotor 10 is formed as illustrated in Figures 6 and 7 with an annular recess 15 to receive the head 11, an intermediate cavity 16 with aligned slots 17 and 18 extended through the walls thereof, and with a hub 19 extended from the closed end providing journaling means of the rotor in the housing. The rotor is also provided with a shaft 20 that extends from the hub 19 and pin receiving openings 21 and 22 are provided in lugs 23 and 24, respectively, in the opposite end. The head 11 is provided with a pin 25 that registers with the opening 22 and a pin 26 that registers with the opening 21, and the head is also provided with a shaft 27 that is aligned with the shaft 20 of the rotor.

35 The blade 12 is designed to slide freely in the slots 17 and 18 across the rotor and the ends are provided with continuous slots 28 and 29 in which contact plates 30 and 31 are positioned and the plates are resiliently held outward by springs 32 and 33. An opening 34 is provided in the center of the blade in which spring holding posts 35 and 36 are held by a bolt 37 with a nut 38. The posts 40 are provided with recesses 39 and 41 respec-

45 50 55

tively which hold the springs 41 and 42 the opposite ends of which bear against the inner surfaces of the lugs 23 and 24 of the rotor. With the position of the blade neutralized by the springs the blade will be prevented from being thrown outwardly against the inner peripheral surface 43 of the housing, thereby preventing excessive wear on the plates 30 and 31.

The inner peripheral surface 43 of the housing is formed by radii the centers of which are dropped downwardly slightly from a point midway between the upper and lower surfaces thereof which is indicated by the numeral 44 and then moved horizontally with the side at the left of the housing illustrated in Figure 3 formed on a radius from the point 45 and the side at the right formed on a radius from the point 46. The upper and lower ends of the arcs are joined by arcs the radii of which are taken from the point 44.

In the lower part of the housing and on the center thereof is a cylindrical opening 47 in which a roller 48 is mounted and the roller is provided with extended pins 49 and 50 at the ends which are rotatably mounted in bearing blocks 51 and 52 by ball bearings 53 and 54. The ends of the roller are resiliently held upward by springs 55 and 56 whereby the upper surface of the roller is held in yielding contact with the rotor 10 and should sand or grit be drawn into the pump, the roller 48 will move downwardly to permit passage thereof.

The pump housing 13 is provided with a cylindrical pump chamber 57, and at one side of the chamber is an annular recess 58 to receive the end of the rotor and another similar recess 59 to receive the hub 19 of the rotor. The housing is provided with an extended hub 60 having a packing gland 61 and a roller bearing 62 therein, and a packing nut 63, is provided at the inner side of the bearing. The outer end of the hub is provided with a cover plate 64 which is held by screws 65. The intermediate part of the housing is provided with inlet and discharge connections 66 and 67 which communicate with the pump chamber 57 and it will be understood that the positions of these connections may be reversed as the pump may either be run in a clockwise or counter-clockwise direction.

The cover plate 14 is mounted on the opposite end of the housing by studs 68 with nuts 69 and this plate is provided with an annular recess 70 to receive this end of the rotor. The cover plate is also provided with a hub 71 having a packing gland 72, a nut 73 and a bearing 74 therein, and the outer end of this hub is provided with a cover plate 75 that is held by bolts 76.

With the parts arranged in this manner the rotor may be driven from either end and as the rotor rotates the blade slides back and forth therein with the plates 30 and 31 in constant wiping contact with the inner peripheral surface 43 of the housing and, as hereinbefore stated, the outward force of the blade is neutralized by the cushioning springs in the center of the rotor whereby the wear on the plates in the ends of the blade is reduced to a minimum.

It will be understood that modifications may be made in the design and arrangement of the parts without departing from the spirit of the invention.

What is claimed is:

1. A rotary pump comprising a housing having a substantially cylindrical pump chamber therein, a rotor having a transversely disposed blade hold-

ing slot therethrough rotatably mounted in the housing and eccentrically positioned in said pump chamber, said rotor having a cavity therein, a blade slidably mounted in the slot of the rotor with both ends thereof extended from the peripheral surface of the rotor and in continuous contact with the inner surface of the cylindrical pump chamber, studs extended from opposite sides of the blade, springs, the axes of which are parallel to the blade spaced from the sides of the blade and positioned between the studs and opposite sides of the inner surface of the rotor for restraining outward travel of the blade, and inlet and discharge connections in the housing communicating with said pump chamber.

2. A rotary pump comprising a housing having a substantially cylindrical pump chamber therein, a rotor having a transversely disposed blade holding slot therethrough rotatably mounted in the housing and eccentrically positioned in the pump chamber, a blade slidably mounted in the slot of the rotor with both ends thereof extended from the peripheral surface of the rotor and in continuous contact with the inner surface of the cylindrical pump chamber, plates resiliently mounted in the ends of the blade providing contact means with the inner peripheral surface of the pump chamber, studs extended from opposite sides of the blade, springs, the axes of which are parallel to the blade spaced from the sides of the blade and positioned between the studs and opposite sides of the inner surface of the rotor for equalizing the position of the blade, and inlet and discharge connections in the housing communicating with the pump chamber.

3. A rotary pump comprising a housing having a substantially cylindrical pump chamber therein, a rotor having aligned shafts extending from both ends and having a transversely disposed blade holding slot therethrough, said rotor having a cavity therein and being rotatably mounted in the housing with one point of the surface thereof contacting the inner peripheral surface of the pump chamber, a blade slidably mounted in the slot in the rotor with both ends thereof in continuous engagement with the inner peripheral surface of the pump chamber, studs extended from opposite sides of the blade, springs, the axes of which are parallel to the blade spaced from the sides of the blade and positioned between the studs and opposite sides of the inner surface of the rotor for equalizing the position of the blade in the rotor, and inlet and discharge connections in the housing communicating with said pump chamber.

4. A rotary pump comprising a housing having a substantially cylindrical pump chamber therein, a rotor having a transversely disposed slot therethrough rotatably mounted in the housing and eccentrically positioned in the pump chamber, a blade slidably mounted in the slot of the rotor with both ends thereof in continuous wiping contact with the inner peripheral surface of the pump chamber, studs extended from opposite sides of the blade, springs, the axes of which are parallel to the blade spaced from the sides of the blade and positioned between the studs and opposite sides of the inner surface of the rotor, a roller rotatably mounted in the housing contacting the rotor, resilient means in the housing positioned at both ends of the roller for urging the roller against the surface of the rotor, and inlet and discharge connections on opposite sides of the rotor.

5. A rotary pump comprising a housing having

a substantially cylindrical pump chamber therein, a rotor having a transversely disposed blade holding slot therethrough rotatably mounted in the housing and eccentrically positioned in the said pump chamber, a blade slidably mounted in the slot of the rotor with both ends thereof in continuous wiping contact with the inner peripheral surface of the pump chamber, said rotor having a cavity therein, studs extended from opposite sides of the blade, springs, the axes of which are parallel to side surfaces of the blade positioned in the cavity of the rotor and connected to the studs on the blade and bearing against the opposite sides of the inner surface of the rotor for providing cushioning means equalizing the travel of the blade in the rotor and restraining outward movement of the said blade in relation to the rotor, and inlet and discharge connections in the housing communicating with the said pump chamber.

6. In a rotary pump, the combination which comprises a housing having a cylindrical pump chamber therein, a rotor having a transversely disposed blade holding slot therethrough journaled in the housing and eccentrically positioned in the said pump chamber, said housing having inlet and outlet connections and said rotor positioned to engage the inner peripheral surface of a cylindrical pump chamber between the said inlet and outlet connections, a blade extended continuously through the rotor slidably mounted in the slot thereof and positioned with both ends in continuous wiping contact with the inner peripheral surface of the pump chamber, said rotor having a cavity in the intermediate part

15

20

30

35

thereof, a stud carried by the blade positioned intermediate of the ends thereof and with the ends of the stud extended from both sides of the blade, cushioning springs carried by the extended ends of the stud and positioned to engage walls on the opposite sides of a cavity of the rotor, said springs urging the blade to a neutral position in the rotor with the ends extended equally at both sides of the rotor, and resiliently actuated means for sealing the point of contact between the surface of the rotor and the inner peripheral surface of the cylindrical pump chamber between the said inlet and outlet connections.
